COIN RECEPTEACLE AND CONVEYER

Frank A. Marchioni, Rutherford, N. J.

Application July 14, 1934, Serial No. 735,125

3 Claims. (Cl. 232—44)

This invention relates to coin handling devices and in particular to mechanisms of the character employed in stores, restaurants, lunchrooms and cafeterias into which the customer deposits the amount of the purchase so that the necessity of the employee handling money is eliminated.

In machines of this kind, heretofore, the deposit has been made in a receptacle having glass sides the coins being temporarily held in view until the attendant operates a lever to drop the coins into a suitable container beneath the counter. Coins that were bent or worn would stick together and the machine would be choked until the accumulated coins were removed, the machine being out of service in the meantime, thus hindering the smooth operation of the employee. To eliminate this fault, I have provided a device in which one of the sight glasses is movable relatively to the other in order that, each time the coins are to be released, the one glass is spread and allows all the coins whether stuck together or not to drop into the receptacle.

Another important object of my invention is to provide, in combination with a plurality of coin receiving devices that are operated by the individual employee at his particular counter, a conveyer which receives all the coins after they pass through the devices and deposits them in a receiving and registering unit or in the cashier's cage where the coins may be sorted and used again as change, as in restaurants where nickels are used for the purchase of food automatically.

My invention eliminates the necessity of a large number of salespeople handling cash and does away with the bookkeeping incidental to assigning each salescounter with a given amount of cash.

Changes and variations may be made in the construction shown and described without departing from the principles of the invention or sacrificing its chief advantages; hence such invention is not to be confined to the structures shown in the accompanying drawings, in which;

Figure 1 is a view in perspective of a counter in which my improved devices are mounted, a coin conveyer being employed in this arrangement to carry the deposited coins to a recording mechanism.

Figure 2 is a section on the line 2—2 of Figure 1 and shows the conveyer arrangement.

Figure 3 is a section on the line 3—3 of Figure 1 showing the conveyer trough construction.

Figure 4 is a top plan view of the end of the conveyer housing as illustrated in Figure 1.

Figure 5 is a section taken on the line 5—5 of

Figure 4 showing the end sprocket and housing arrangement of the coin conveyer.

Figure 6 is a view in elevation of a coin receptacle looking from the operating side thereof, the handle being broken to disclose the parts.

Figure 7 is a section taken on the line 7—7 of Figure 6 showing how the glasses are mounted in the receptacle casing so that one may be moved away from the other to separate and allow wedged coins to drop into the coin box disposed below the receptacle.

Figure 8 is a vertical section taken on the line 8—8 of Figure 6 showing the mechanism for operating one of the sight glasses and permitting the coins to fall through the coin device.

Referring to the drawings in detail, and in particular to Figures 1 to 5 inclusive, the numeral 5 indicates a counter as employed in self service lunchrooms, stores and the like and over which purchases are made, the cost of the purchases being paid in coins of any denomination which are dropped into the coin receptacles 6 which are mounted along the edge of said counter.

These coin receptacles 6 are provided with windows or sight glass panes 7 between which the coins are disposed until the counter attendant manipulates a handle 8 either directly or through the medium of a linkage 9 to drop the coins into a conveyer housing 10. The coin receptacle 6 is provided with a hollow base portion 11 through which the coins drop, the bottom of the base resting on the bracket 12, through which the coin conveyer housing passes and through the medium of which the housing is supported on the counter.

The housing 10 is a channel shaped member in the bottom of which is placed a rectangular tube 13 to provide a passage for the conveyer chain 14, the upper reach of which travels along the bottom of an inner channel member 15 secured in any suitable manner to the top of the tube 13. The brackets 12 form a top closure for the housing at the points where the coin devices are disposed, and between the devices, the housing is closed by a cover strip 16 which may rest on the upper edges of the inner channel member 15 and be secured thereto as desired.

The sprocket or conveyer chain 14 is driven over usual sprocket wheels 17, only the one at the discharge end of the housing being shown, where a discharge elbow 18 closes the end of the housing 10 and also serves as a journal for the sprocket shaft 19, whose end beyond the elbow 18 carries the gear 20 operated by the pinion 21 which

is driven in any suitable manner from the motor 22.

The motor operating continuously causes the chain to convey the coins that fall through the 5 coin device to the end of the housing where they fall through the elbow and into a receiving box 23 to pass through a suitable registering unit whose construction is not a part of my invention. The unit may be simply a coin sorting device if desired and may be disposed inside a cashier's cage if desired so that the coins returned may be used by the cashier in making change for the customers. My invention is particularly directed to the combination of conveyer 10 with coin receptacles and any arrangement desired 15 may be employed.

In order to facilitate the operation of the coin receptacle handle 8 in wide counters, I may secure a link 24 thereto whose lower end may be pivoted as at 25 to a horizontal yoke member 26 which extends the width of the counter and whose inner end is pivoted as at 27 to one of the counter uprights 28. The outer end of the yoke has a handle 29 thereon, through which the coins 20 in the coin device are dropped into the conveyer or into a coin box as desired. The ends of the housing members or channels are secured in the elbow 18 in any suitable manner.

The most important feature of my invention 30 as disclosed in Figures 6, 7 and 8 is the use of a coin receptacle employing a novel means of preventing the coins from jamming or blocking up the device and the device 6 referred to as a coin receptacle comprises the casing 30 the upper 35 end of which is open and the opposite sides of which are provided with sight openings 31. The upper end of the casing 30 is closed by the slot piece 32 in the slot 33 of which is deposited the coins used in paying for purchases and of any 40 denomination desired. The slot piece 32 has fixed thereto in any suitable manner, the depending channels 34, the edges of which are serrated as at 35 to hold the glass pane 36 frictionally in place. These channels also carry dowel pins 37 which 45 fit into sockets 38 of similar channels 39 to support the channels 39, the same being yieldably sustained in contact with the channels 34 so that the glass pane in channels 34 and a similar glass pane in channels 39, denoted by numeral 40, are 50 maintained in proper spaced relation to provide a receptacle for deposited coins 41 so that they may be seen through the sight openings in the casing by the customer and the counter attendant. Beneath the sight openings in the casing, 55 the latter is chambered to receive a coin dropper 42, the end flanges 43 of which carry studs 44 which are journaled in the cups 45 cast integral with the closure disks 46A secured in any suitable manner in the casing 30.

The disks or flanges 43 are connected by the cross portions 46 and 47, in the latter of which is threaded a handle stud 48 carrying exteriorly of the casing, a spring housing piece 49 which operates between side flanges 50 and limits the 60 upward movement of the handle by contact with an upper boss 51 and a lower boss 52; the spring 53 maintaining the handle in raised position and the coin dropper in such position that the cross piece 47 thereof closes the space between the 65 panes of glass at the bottom thereof to support the coins in view until the handle is depressed. Any length of handle 54 may be secured to the outer end of the stud 48.

The space 55 separating the portions 46 and 47

will be in alignment with the space between the panes when the handle is depressed so that coins in the said space will drop through the casing and coin dropper into a suitable box or onto the conveyer as described. In devices of this character where the panes have been mounted in relatively fixed channels, bent or mutilated coins have become wedged between the panes and the machine has been jammed. In order to overcome this objection, I interpose a leaf spring 56 at 10 each side of the casing, bearing thereon, and also against the channels 39. The lower edges of these channels are extended as at 57 into a notch 58 cut in the flanges 43 of the coin dropper 42. Upon a downward movement of the handle 54, the 15 coin dropper swings the lower end of the channels 39 as indicated in outline in Figure 8 to separate the glass panes and drop any coins that have become jammed between the panes, through the space 55 of the coin dropper and into the conveyer or box. The only need for removing the panes would be for the purpose of cleaning the same and in order to prevent removal thereof by an unauthorized person, I employ a depending tab or extension 59 on the part 32 to carry 20 a pin 60 which underlies the bolt of a lock 61 which is secured in any suitable manner in the casing 30.

In order to support the channels 34, in the casing, use is made of extension support pieces 30 62 which are cast integral with the closure disks 46A and engage in suitable cut-outs 63 in the bottom ends of the channels 34.

It is evident therefore that I have provided a coin receptacle which is jam proof and which 35 operates automatically when dropping coins to separate the glass panes so that coins sticking therebetween are dropped and the machine is not out of service due to coins becoming stuck in the coin passage between the panes.

It is also evident that I have provided in connection with a number of coin receptacles, a conveyer which eliminates the necessity of collecting the coins from each individual coin device and also makes it possible to use the returned 45 coins in making change from the cashier's cage.

My invention is not to be restricted to the precise details of construction shown since various changes and modifications may be made therein without departing from the scope of the invention or sacrificing the advantages derived 50 from its use.

What I claim is:

1. A coin handling device for store counters 55 or the like including a casing having opposite sight openings therein, spaced panes of glass in the casing, the space between the panes constituting a coin receptacle where the coins are supported in display position, a coin dropper for supporting the coins when in one position and for dropping them through the device into a receptacle when in another position, means for operating said dropper and means extending from one of the panes into the dropper and arranged to be moved by manipulation thereof to spread the panes apart to allow wedged coins to drop through the device.

2. A coin handling device including a casing having sight openings therein, channel frames, 70 glass panes removably held in said frames and spaced apart to provide a coin chamber, a coin dropper for supporting the coins between the panes and dropping them into a receptacle, means for operating the dropper, and said dropper being 75

arranged to spread said panes automatically upon a coin dropping movement thereof.

5. A coin device including a casing, spaced walls in the casing providing therebetween a coin receptacle, a coin dropper for supporting the coins between the walls and dropping them into a receptacle, notches in said dropper exten-

sions on one of the walls extending into said notches, whereby when the dropper is operated, the walls are spaced further apart to free jammed coins, and a spring for yieldably resisting the movement of one of said walls.

5

FRANK A. MARCHIONI.
